UNITED STATES PATENT OFFICE.

ANTON BUEDALL, OF SHERIDAN, OREGON.

PEN AND PENCIL HOLDER.

Application filed May 1, 1924. Serial No. 710,352.

To all whom it may concern:

Be it known that I, ANTON BUEDALL, a citizen of the United States, residing at Sheridan, in the county of Yamhill and State of Oregon, have invented certain new and useful Improvements in a Pen and Pencil Holder, of which the following is a specification.

This invention relates to new and useful improvements in pen and pencil holders and has for its principal object to provide a simple and efficient device which may be attached to and worn on the wrist of a person, means being provided for normally holding the pen or pencil or both in a retracted position.

A further object of the invention is to provide a device of the above mentioned character, wherein means is provided for enabling a person to at all times have at hand a pen or pencil which may be used whenever desired, thus preventing the loss of considerable time in looking for a pen or pencil as is often experienced.

25 A still further object of the invention is to provide a device of the above mentioned character, wherein a holder is provided which may be conveniently worn on the wrist of a person and in such a manner as 30 to support a plurality of pens and pencils, means being associated therewith for normally holding the pens and pencils in a retracted position when not in use, means being further provided for projecting the pen or pencil to be used upon the releasing of the holding means whereby a pen or pencil may be withdrawn from the holder and used by the person without interfering with the other pencils in the holder.

40 A still further object of the invention is to provide a device of the above mentioned character, which includes a means for detachably securing the same around the wrist of the wearer and will further provide a simple and efficient means for holding a plurality of pens or pencils, thus obviating the necessity of having to carry the pens or pencils in the pocket or other part of the person's apparel.

45 A still further object is to provide a device of the above mentioned character, which is simple in construction, inexpensive, strong and durable and furthermore adapted for the purposes for which it is designated.

50 Other objects and advantages of this in-

vention will become apparent during the course of the following description.

In the accompanying drawings forming a part of this specification, and in which like numerals designate like parts throughout the same:

Figure 1 is a side elevation of my invention.

Figure 2 is a vertical section taken approximately on line 2—2 of Figure 1.

Figure 3 is a sectional view at right angles to Figure 2.

Figure 4 is a transverse section taken approximately on line 4—4 of Figure 1.

Figure 5 is a similar view taken on line 5—5 of Figure 1, and

Figure 6 is a fragmentary view of a modification of the attaching means.

In the drawing wherein for the purpose of illustration is shown the preferred embodiment of my invention, the numeral 1 designates a substantially rectangular casing, the same being formed of any suitable material. Extending transversely in the casing 1 adjacent the upper portion thereof is the partition 2 which forms a compartment 3 in the top of the casing, and as clearly illustrated, the upper end of the casing is threaded to receive thereon the cover 4. The lower end of the casing 1 is open and extending longitudinally from the bottom of the casing to the partition 2 are the compartments 5, any number of which may be provided as is desired. The compartments 5 are preferably cylindrical in cross section as is clearly shown in Figure 5 of the drawings and the purpose thereof is to provide a means for receiving therein the various pens or pencils such as are shown at 6 and 7 respectively with reference more particularly to Figure 3 of the drawings.

The pens and pencils it is to be understood are of such a length as to be received in the compartments provided therefor and in such a manner as to normally have the lower ends of the pens and pencils disposed inwardly from the bottom of the casing in the manner clearly illustrated in Figures 2 and 3 of the drawings. The upper ends of the pens and pencils are provided with suitable projections such as are shown at 8 and the projections are provided with eyes whereby means is provided for attaching to the upper ends of the pens and pencils one end of the chain 9. Each chain extends through a suitable opening provided in the

partition 2 arranged in communication with the respective compartments in the manner shown at 10 and the upper end of each chain is wound around a spring reel 11. As many spring reels are provided as there are compartments and pencils or pens therein and the reels are of the usual construction, the same being well known in the art. The reels are further supported in the compartment 3 formed in the top of the casing 2 and are supported on the transversely extending rods 12. The spring reels 11 normally keep the pencils and pens within the compartments in the casing in a retracted position and when the pens or pencils are in use, it is to be understood that the chain 10 will be unwound from its respective reel. It is also to be understood that each chain is of a suitable length so as to enable the pencil or pen attached thereto to be withdrawn from the casing and held in the hand of the person in such a manner as to facilitate the proper use thereof.

In order to enable the desired pen or pencil to be extracted from its respective compartment in the casing so that the person may use the same, I provide in each compartment a plate 13 which has an opening 14 therein adapted to receive the projection 18 formed on the upper end of each pencil or pen and so as to permit the plate to rest on each pen or pencil. A coil spring such as is shown at 15, is disposed between each plate and the bottom face of the partition 2. The coil springs 15 thus provide a means whereby the lower ends of the pens or pencils may be projected outwardly from the bottom of the casing so as to permit the person to grasp the pen or pencil projected in order to withdraw the pen or pencil from its compartment in the casing whenever it is desired to use the same.

For the purpose of holding the lower end of the pens or pencils within the casing and normally keeping the coil springs under tension, I provide each compartment with a lever 16. Each lever is pivoted intermediate its ends as shown at 17 in a slot 18 formed in the front side of each of the compartments adjacent the bottom of the casing. The upper end of each lever extends inwardly into each compartment and engages the pen or pencil supported therein. The lower end of the lever is disposed outwardly of the casing and a suitable coil spring 19 is associated with each lever at the lower end thereof for normally keeping the upper end of the lever in engagement with the respective pen or pencil. A finger piece 20 is mounted on the lower end of each lever and provides a means whereby the person may push inwardly on the lever for releasing the upper end thereof from engagement with the desired pen or pencil so that the spring in the compartment which supports

the lever which has been released will project the lower end of the pen or pencil outwardly from the bottom of the casing so that the same may be withdrawn by the person when it is desired to use the same.

For the purpose of attaching the casing 1 and the pens and pencils supported thereon to the wrist of a person, I provide the straps 21 and 22 respectively arranged adjacent the upper and lower ends of the casing and secured thereto in any suitable manner. The ends of the strap are provided with the usual cooperating fastening means such as is shown at 23 and 24 and I do not wish to limit myself to any particular manner in which the ends of the strap are to be fastened around the wrist of the wearer. If further desired, a watch such as is shown at 25 may be supported on one of the straps in the usual manner, thus providing a wrist support for both the pen and pencil holder and the watch.

In Figure 6 of the drawings I have shown a modification of wrist attaching means wherein the fastening strap 26 is of one piece and tapers gradually toward the outer ends thereof and on which is arranged the usual fastening means. The watch 25 may also be supported on the strap 26 in any well known manner.

It will thus be seen from the foregoing description, that a pen and pencil holder has been provided wherein any number of pens or pencils may be supported in the casing on the wrist of the wearer in such a manner as to be accessible at all times, thus preventing the necessity of having to carry the pens and pencils around in the pockets of the person or in any other place which frequently results in the loss of the pen or pencil as well as the loss of considerable time in trying to find a pen or pencil when it is desired to have the use of the same. The use of my device is such as to permit either a pen or pencil to be retracted from the casing after the particular lever has been released from engagement with the lower end of the pen or pencil and the coil spring associated therewith has caused the lower end of the pencil to be projected outwardly from the bottom of the casing. After the pencil or pen has been used, the spring reel 11 will cause the chain 10 to be wound around the same and retract the pen or pencil into its particular compartment and the lever will then automatically lock the lower end of the same inwardly from the bottom of the casing.

The simplicity of my device enables the same to be manufactured at a very low cost, be strong and durable and may be worn on the wrist of the person without inconvenience and will at all times provide a means whereby a pen or pencil will be accessible and ready for use.

While I have shown the preferred embodiment of my invention, it is to be understood that various changes in the size, shape and arrangement of parts may be resorted to without departing from the spirit of the invention and the scope of the appended claims.

Having thus described my invention, what I claim is:—

- 10 1. A pen and pencil holder of the class described comprising a casing open at its bottom, a pencil supported at its upper end therein, means for holding said pencil in said casing, means for projecting said pencil outwardly from the bottom of the casing when said holding means is released, and a spring reel for retracting said pencil into said casing.
- 20 2. A pen and pencil holder of the class described comprising a casing open at its bottom, a spring reel supported in the top of said casing, a chain fastened at one end thereto and adapted to be wound therearound, a pencil fastened at its upper end to the opposite end of said chain, means carried by the lower part of said casing for engaging and holding the pencil in said casing.
- 30 3. A pen and pencil holder of the class described comprising a casing open at its bottom, a spring reel supported in the top of said casing, a chain fastened at one end thereto and adapted to be wound therearound, a pencil fastened at its upper end to the opposite end of said chain, means carried by the lower part of said casing for engaging and holding the pencil in said casing, and a spring associated with the upper end of said pencil and said casing for

projecting the lower end of the pencil outwardly from the bottom of the casing upon the release of said holding means.

4. A pen and pencil holder of the class described comprising a casing open at its bottom, a spring reel supported in the top of said casing, a chain fastened at one end thereto and adapted to be wound therearound, a pencil fastened at its upper end to the opposite end of said chain, means carried by the lower part of said casing for engaging and holding the pencil in said casing, said means comprising a lever pivotally supported intermediate its ends on said casing, the upper end of said lever extending through the casing and engaging the pencil, a spring associated with the outer free end of said lever and said casing for holding the upper inner end of the lever in engagement with the pencil.

5. A pen and pencil holder of the class described comprising a casing open at its bottom, a spring reel supported in the top of said casing, a chain fastened at one end thereto and adapted to be wound therearound, a pencil fastened at its upper end to the opposite end of said chain, means carried by the lower part of said casing for engaging and holding the pencil in said casing, a spring associated with the upper end of said pencil and said casing for projecting the lower end of the pencil outwardly from the bottom of the casing upon the release of said holding means, and attaching means associated with said casing.

In testimony whereof I affix my signature.

ANTON BUEDALL.
